CLAIM

The ornamental design for a portable mobile-device charger compatible with a removable shell, as shown and described.

DESCRIPTION

FIG. 1 is a perspective view of the portable mobile-device charger compatible with a removable shell showing my new design with the shell that is not included in the claim shown removed;

FIG. 2 is a perspective view showing the shell partially removed to illustrate the design in a position of use;

FIG. 3 is a top plan view of the portable mobile-device charger compatible with a removable shell;

FIG. 4 is a bottom view thereof;

FIG. 5 is a rear elevational view thereof;

FIG. 6 is a front elevational view thereof;

FIG. 7 is a left side elevational view thereof; and,

FIG. 8 is a right side elevational view thereof.

The broken lines in the drawings depict portions of the article that are not included in the claim.
